UNITED STATES PATENT OFFICE.

TRUESDELL COOPER AND JANE H. BRIGANCE, OF DENVER, COLORADO.

FOUNDATION-LINING FOR MATERNITY-GOWNS.

1,000,718.

Specification of Letters Patent. Patented Aug. 15, 1911.

Application filed March 13, 1911. Serial No. 614,199.

To all whom it may concern:

Be it known that we, TRUESDELL COOPER and JANE H. BRIGANCE, both citizens of the United States, residing at Denver, county of Denver, and State of Colorado, have invented a certain new and useful Foundation-Lining for Maternity-Gowns, of which the following is a specification.

The object of this invention is to provide 10 a novel form or foundation on which to drape maternity gowns.

A further object of this invention is to provide what we call a foundation lining constructed somewhat on the lines of a cor- 15 set waist and which is made in two halves or sections connected by laces at the front and by hooks and eyes at the back. Each section of the form comprises a back piece, a side piece and a front piece connected by 20 seams and having light bones inserted along the seam lines to give slight and easy support. The shoulder straps are adjustable in length to vary the position of the form vertically.

25 The laced front is covered by a full or loose curtain which conceals the lacing and prevents the covering or dress goods of the gown from injury by coming in contact with the laces or eyelets. The curtain is 30 loose at the bottom and it is connected at its side edges with the sides of the garment along the lines of the seams which connect the side pieces thereof with the front pieces. The curtain has considerable fullness and its 35 width may be adjusted by a draw string connected with its upper edge which is attached to the opposite side edges of the front pieces near the top thereof.

In the drawings, Figure 1 is a perspective view of the front part of our improved foundation lining. Fig. 2 is a similar view of the rear portion thereof. Fig. 3 is a perspective view of the front portion of the garment with the curtain torn open to expose the lacing. Fig. 4 is a top plan view of the middle portion of the garment.

The garment is made in two halves or sections A and B, each of which comprises a front piece or form *a*, a side piece or form *b*, and a back piece or form *c*. These are suitably shaped to form when sewed together a foundation lining of the general form or shape shown in the drawings. Light bones *x* are inserted in the seams or wherever necessary to give light and easy support. The back pieces or back forms *c* are gath-

ered at *c'* to give the desired shape at the waist and these can be let out or taken in as often as required. The adjacent free edges of the two back pieces are provided with hooks and eyes *d* for fastening them together and the adjacent edges of the front pieces are connected by laces *e*.

The side pieces or side forms *b* and the back pieces or forms *c* are provided with shoulder pieces *f*, *g*, which overlap as shown and form shoulder straps. The overlapping shoulder pieces may be connected by safety pins *D* and these straps may be so adjusted in length as to vary the height of the form on the wearer and thus vary the height of the waist of the gown applied to the form. By means of the laces the garment may be enlarged or reduced transversely as occasion may require.

In order to conceal the laces and the opening between the adjacent edges of the two front pieces, and in general to conceal the corset effect of the foundation lining, we provide a curtain *E*. This is made loose or full as shown extending from the top of the garment to the bottom thereof, being attached to the garment along the seam lines between the front and side forms. The bottom of the curtain is unattached while the top edge thereof is provided with a draw string *F* which extends through eyelets in the front forms *a* and is formed with bow-knots, or other suitable devices *m*, to prevent it from getting out of place. In this way the width of the curtain at the top can be varied as required.

When the foundation lining is properly adjusted the gown may be readily draped thereon and adjusted thereto, and the lining and dress goods may be afterward adjusted or changed as often as required. By letting out the shoulder straps the gown may be lowered or raised to the desired extent. The curtain hangs between the foundation and the waist and as before stated conceals the lacing employed to connect the front pieces of the foundation.

We claim as our invention:

1. A foundation lining for maternity gowns made in two formed sections separably connected along vertical meeting edges at the back and adjustably connected along vertical edges in front whereby the dimensions of the front of the lining may be varied, and a curtain hiding the front adjustable connections and having its edges

permanently connected to the two formed sections, said curtain being of greater width than the lining between the edges of the curtain, whereby the adjustable connections are concealed and a full and loose effect given regardless of the adjustment of the lining sections.

2. A foundation lining for maternity gowns made in two formed sections, each 10 having an adjustable shoulder strap, said sections being separably connected along vertical edges at the back and adjustably connected along vertical edges in front, whereby the dimensions of the lining may 15 be varied, and the height of the waist line adjusted, each of said sections being gath-

ered at the waist line in the back and a full integral curtain having its edges connected with the sections on opposite sides of the adjustable front fastening to conceal said fastening and give a full effect regardless of the adjustment, said curtain being free at the top and bottom edges and having an adjusting cord in its upper edge. 20

In testimony whereof we have hereunto 25 subscribed our names.

TRUESDELL COOPER.
JANE H. BRIGANCE.
